UNITED STATES PATENT OFFICE.

JULIA M. MURRAY, OF ST. LOUIS, MISSOURI.

DESIGN FOR A CRIB MOUNTING.

Application filed April 10, 1923. Serial No. 5,765. Term of patent 3½ years.

To all whom it may concern:

Be it known that I, JULIA M. MURRAY, a citizen of the United States, residing at St. Louis, in the State of Missouri, have invented a new, original, and ornamental Design for Crib Mounting, of which the following is a specification, reference being had to the accompanying drawing, forming part thereof.

Figure 1 is a perspective view of a crib mounting, showing my new design.

Figure 2 is a top view of the same.

The design consists in a cave or grotto in a mass rising above a relatively low flat

area which forms the base of the design and from which spring a few scattered trees. The grotto portion extends substantially diagonally across the base and the plain surface in front of the grotto is adapted to form a mounting for loose separate figures commonly associated with the Nativity, such as the Mother and Child, Joseph, shepherds, Magi, sheep, camels, etc.

I claim:

The ornamental design for a crib mounting, as shown, and described.

JULIA M. MURRAY.
